CLAIM

The ornamental design for a cryo puck, as shown and described.

DESCRIPTION

FIG. 1 shows a perspective view of a cryo puck; FIG. 2 is a plan view of the upper surface of the cryo puck shown in FIG. 1;

FIG. 3 is a side view of the cryo puck shown in FIG. 1; FIG. 4 is a side view of the cryo puck shown in FIG. 1; FIG. 5 is a plan view of the lower surface of the cryo puck shown in FIG. 1;

FIG. 6 is a side view of the cryo puck shown in FIG. 1; and, FIG. 7 is a side view of the cryo puck shown in FIG. 1. The broken lines indicated in the Figures illustrate portions of the cryo puck that form no part of the claimed design.

1 Claim, 7 Drawing Sheets
